COMBINED DISPLAY CUBE AND STAND THEREFOR

Marshall C. Schneider, Newton Center, Mass., assignor to Charles D. Barnes Co.

Filed May 26, 1971, Ser. No. 147,294

Term of patent 14 years

Int. Cl. D6—06

U.S. Cl. D6—235

Fig. 1

Fig. 3

FIG. 1 is a perspective view of a combined display cube and stand therefor showing my new design;

FIG. 2 is a top plan view thereof; and

FIG. 3 is an elevational view thereof taken from the left side of FIG. 1.

I claim:

The ornamental design for a combined display cube and stand therefor, as shown.
